(57) **CLAIM**

I claim the ornamental design for the sand and water box, as shown and described.

DESCRIPTION

FIG. 1 is a perspective of a sand and water box;

FIG. 2 is an exploded perspective view of the sand and water box, including a container and lid;

FIG. 3 is a top plan view of the container of the sand and water box;

FIG. 4 is a bottom plan view of the container of the sand and water box;

FIG. 5 is a left elevation view of the container of the sand and water box, the right side of which is a mirror image;

FIG. 6 is a front elevation view of the container of the sand and water box, the rear of which is a mirror image;

FIG. 7 is a top plan view of the lid of the sand and water box;

FIG. 8 is a bottom plan view of the lid of the sand and water box;

FIG. 9 is a right elevation view of the lid of the sand and water box;

FIG. 10 is a left elevation view of the lid of the sand and water box;

FIG. 11 is a front elevation view of the lid of the sand and water box; and,

FIG. 12 is a rear elevation view of the lid of the sand and water box.
